UNITED STATES PATENT OFFICE.

ROBERT S. CADE, OF CANTON, OHIO.

COPING.

1,178,623.

Specification of Letters Patent.

Patented Apr. 11, 1916.

Application filed April 23, 1915. Serial No. 23,367.

To all whom it may concern:

Be it known that I, ROBERT S. CADE, a citizen of the United States, residing at Canton, in the county of Stark and State of

5 Ohio, have invented a new and useful Coping, of which the following is a specification.

My invention has relation to coping for walls, and has more especial reference to a novel form of coping adapted to be applied 10 to a wall where said wall forms an abutment for a terrace or lawn of greater height than the wall.

The object of my invention is to provide a coping adapted to be applied to a wall, 15 where said wall forms an abutment for a terrace or lawn of greater height than the wall.

Another object is to provide a coping adapted to be applied to a wall by means of 20 which a terrace may be extended over the entire top surface of the wall.

With these objects in view the invention consists in the novel construction and arrangement of parts, hereinafter described, 25 illustrated in the accompanying drawings, and particularly pointed out in the appended claim, it being understood that various changes in the form, proportions, size and minor details of construction may be made 30 within the scope of the appended claim, without departing from the spirit or sacrificing any of the advantages of the invention.

In the drawings: Figure 1 is a sectional 35 perspective view of a portion of an embankment and a breast-wall with my improved coping in position thereon. Fig. 2 is a perspective view of a section of the coping.

40 Similar numerals of reference indicate corresponding parts throughout the several figures of the drawings.

In the drawing the numeral 1 indicates a breast-wall built against an embankment 2. 45 The coping is made in sections such as illustrated in Fig. 2, each section comprising the rectangular ledge 3, which is adapted to extend across the top of the wall 1 and is provided with the elongated slot 4 located 50 substantially through the longitudinal center of said ledge portion, and the flange 5 which is provided along the outer edge of the ledge portion, said flange preferably forming an obtuse angle with the ledge portion as shown. The flange 5 is preferably 55 provided with a longitudinal rib 6 along its

upper outer edge and any suitable form of decoration may be applied to the outer face of the flange for the purpose of ornamentation.

60 The sections of coping are placed in longitudinal alinement upon the top face of the wall, the slots 4 in said sections registering with a longitudinal groove 7, which is located in the top of the wall 1. Cement or 65 similar material, as indicated at 8, is poured through the slots 4, filling said slots and the groove 7 and when the cement sets or hardens the sections of coping are rigidly held in position from the top of the wall, in 70 the position shown in Fig. 1. If desired, the sections of coping may be bound together at their extremities by means of mortar or similar material.

75 When the mortar or cement used in binding the sections of coping to the wall has hardened the coping may be filled in with earth, thus extending the terrace across the entire top surface of the breast-wall as shown in Fig. 1 of the drawings. By this 80 construction it is possible to increase the size of the lawn considerably, or if desired a flower bed may be located adjacent the flange of the coping.

85 For the purpose of preventing moisture in the earth above the coping from running down upon the rear side of the breast-wall and possibly causing the same to crack or break, a series of drain apertures 9 are located at intervals along the ledge 3, the 90 lower extremities of said apertures being located beyond the outside face of the breast wall, thus causing any moisture which accumulates above the coping to be carried off away from the breast-wall.

95 Although the drawings and above specification disclose the best mode in which I have contemplated embodying my invention I desire to be not limited to the details of such disclosure, for, in the further practical 100 application of my invention, many changes in form and construction may be made, as circumstances require or experience suggests, without departing from the spirit of the invention, within the scope of the appended 105 claim.

I claim:

110 A coping comprising a rectangular ledge portion arranged to be located upon the top of a breast-wall, said ledge provided with a centrally located elongated slot adapted to receive a cement binder and with a plu-

rality of draining apertures extending through said ledge, the lower extremities of said apertures being along the outer edge of the ledge and an upwardly projecting flange located along the outer edge of said ledge.

In testimony that I claim the above, I

have hereunto subscribed my name in the presence of two witnesses.

ROBERT S. CADE.

Witnesses:

J. H. BISHOP,
SYLVIA BORON.
